(57) **CLAIM**

The ornamental design for a firearm lower receiver, as shown and described.

DESCRIPTION

FIG. 1 is a rear left isometric view of the firearm lower receiver;

FIG. 2 is a rear right isometric view thereof;

FIG. 3 is a rear elevational view thereof;

FIG. 4 is a front elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a cross sectional view taken along line 9-9 of FIG. 3.

The portions of the firearm lower receiver depicted in broken dash lines represent the bounds of the claim and form no part of the claimed design.
